UNITED STATES PATENT OFFICE.

LOUIS W. G. FLYNT, OF ROCHESTER, NEW YORK, ASSIGNOR TO DOMESTIC APPLIANCES COMPANY, OF ROCHESTER, NEW YORK, A CORPORATION OF NEW YORK.

SAFETY DEVICE FOR GAS-BURNERS.

1,027,534.

Specification of Letters Patent.

Patented May 28, 1912.

Original application filed April 10, 1911, Serial No. 620,113. Divided and this application filed June 26, 1911. Serial No. 635,510.

To all whom it may concern:

Be it known that I, LOUIS W. G. FLYNT, a subject of the King of Great Britain, and resident of Rochester, in the county of Monroe and State of New York, have invented certain new and useful Improvements in Safety Devices for Gas-Burners, of which the following is a specification.

This invention relates to steam-generators, 10 gas-ovens, or other devices in which gas-burners are employed.

Where a gas-burner is employed in an inclosed space for heating purposes, as in a gas-oven, steam-generator, or the like, a 15 pilot-light is usually provided in order that the burner may be lighted immediately when the gas is turned on. In case a pilot-light is not so provided, however, or is not lighted before the gas is admitted to the 20 burner, the unburnt gas issuing from the burner is liable to collect in the casing or oven and form an explosive mixture, so that if it be attempted to light the burner a dangerous explosion results.

25 The object of the present invention is to prevent such explosions, and to this end I provide apparatus of the kind in question with means which operate automatically, when the gas is flowing from the burner, to 30 prevent the operator from lighting the burner or the contents of the casing or oven, so that it is necessary either to light the pilot-light before turning on the gas, or else to turn off the gas before access can be 35 had to the burner for the purpose of lighting the burner or the pilot-light.

In the drawings:—Figure 1 is a horizontal section, on the line 1—1 in Fig. 2, of a portion of a steam-generator in connection 40 with which the present invention is employed; Fig. 2 is a vertical section on the line 2—2 in Fig. 1; and Fig. 3 is a horizontal section on the line A—A in Fig. 2.

The invention is illustrated as embodied 45 in a steam-generator of the type disclosed in my copending application Serial No. 620,113, filed April 10, 1911, of which the present application is a division. The burner is a hollow casting 3 provided at the 50 top with slots for the escape of the gas and air. This burner is located at the bottom of a cylindrical casing 4 inclosing the boiler which is heated by the burner. The casing 4 is provided at one side with a door-way

which affords access to the burner and the 55 pilot-light, and this door-way is normally closed by a door 5, depending from a pivot 6 by which it is hinged to the casing. The burner is fed with gas through a nozzle 7. Within the gas-nozzle is a steam-jet nozzle 60 8 which is employed to inject the gas, although this arrangement constitutes no part of the present invention. The gas-nozzle is supplied through a conduit 9 into which the gas is admitted through an opening 65 controlled by a gas-valve 10. The gas-valve moves in a chamber 11 which is fed from a gas-supply pipe 12. The gas-valve 10 is automatically controlled by a dia- 70 phragm-mechanism described more fully in my said application. To this end the valve is mounted on a stem 13 connected with a flexible diaphragm 14. At the left of the diaphragm is a chamber 15 which is in communication, through a tube 16, a T 17 and 75 a tube 18, with the boiler which is heated by the burner 3, the diaphragm being thus subjected, on its left-hand surface, to the boiler pressure. At the right of the dia- 80 phragm is a casing 19 which is connected, through a tube 20, with a source of water under pressure from which the feed-water for the boiler is obtained. The resiliency of the diaphragm 14 tends normally to close the gas-valve, thus interrupting the supply 85 of gas to the burner. When the feed-water is introduced under pressure through the tube 20, however, the pressure of the water acts to open the gas-valve and thus to admit 90 gas to the burner.

As the boiler is heated the boiler-pressure communicated to the chamber 15 tends to counteract the pressure of the feed-water upon the diaphragm, and the flow of gas is thus governed in the manner described 95 in my said application. It will be noted that the gas-valve is never open except when there is pressure within the casing 19, and I take advantage of this fact in operating an automatic device for locking the door 5 in closed position. To this end a second diaphragm 23 is inclosed within the casing 19, and from this diaphragm a rod 24 ex- 100 tends horizontally into engagement with the short end of a bell-crank lever 25. The other arm of this lever engages a vertically-sliding bolt 26, of which the upper end is adapted to engage an opening in a lug 27

on the door 5. A coiled spring 28, acting against a head on the lower end of the bolt 26, tends to force the bolt downwardly so as to unlock the door. As soon, however, 5 as feed-water is admitted to the casing 19, the diaphragm 23 is moved to the right, thus causing the bell-crank lever to raise the bolt into operative engagement with the door. It is impossible thereafter to open 10 the door until the water-pressure has been relieved, and accordingly the door cannot be opened while the gas-valve is held open by its diaphragm 14.

As it is inconvenient to light the burner 15 directly, a pilot-light 29 is provided for this purpose, the pilot-light being fed with gas through a tube 30 which extends from the valve-casing 11 and is controlled by a valve 31. When there is no pressure in the dia-

20 phragm-casing 19 and the gas-valve 10 is closed, the door 5 may be opened and the pilot-light lighted. The door, when released, closes itself automatically owing to the fact that it is suspended from above.

25 When the feed-water is introduced through the tube 20, thus opening the gas-valve 10, the gas flows into the burner, and is ignited from the pilot-light. From the diaphragm casing 19 the feed-water flows

30 through an automatic controlling-device 21, which constitutes no part of the present invention, and from this device the water flows through a tube 18 to the boiler. The pilot-light normally remains lighted even

35 when the generator is out of operation, so that it is ordinarily necessary only to turn on the feed-water in order to start the burner. In case the pilot-light should go out, however, or be turned out for any

40 purpose, the operator of the generator being unaware of this fact, or through carelessness, might first turn on the feed-water and admit gas to the burner, and then attempt to open the door to light the pilot-light. In

45 such a case the bolt 26 operates to lock the door, and before the door can be opened it is necessary to turn off the feed-water, and consequently the gas, and also to wait for an interval of time during which the water

50 which has accumulated under pressure between the diaphragms 14 and 23 slowly escapes through the feed-water regulator into the generator. During this interval the gas which has been admitted to the cas-

55 ing has an opportunity to escape therefrom, so that when the pressure between the dia- phragms is finally relieved and the door is unlocked there is no further danger of ex- plosion.

60 I claim:

1. The combination of a combustion chamber, a gas burner therein, a gas valve for controlling the flow of gas through the burner, a movable part that when in 65 one position bars access to the burner to

light it, and when in another position gives access to the burner for that purpose, and unitary means for opening the gas valve and locking said part in the position first mentioned whereby its movement to give 70 access to the burner is automatically prevented after the gas valve is open.

2. The combination of a combustion chamber, a gas burner therein, a gas valve controlling the flow of gas to the burner, a movable part that when in one position bars access to the burner to light it and when in another position gives access to the burner for that purpose, and automatic means adapted to operate with the opening of the gas valve to lock said movable part in the position first mentioned for preventing ignition of the burner. 80

3. The combination of a combustion-chamber, a gas-burner therein, a gas-valve 85 for controlling the flow of gas through the burner, a door affording access to the combustion-chamber to light the burner, and unitary means for opening the gas-valve and locking the door in closed position, 90 whereby opening of the door is automatically prevented after the gas-valve has opened.

4. The combination of a combustion chamber, a gas burner therein, a gas valve 95 controlling the admission of gas to the burner, a pilot-light for lighting the burner, a movable part that when in one position bars access to the pilot-light to light it, and when in another position gives access 100 to the pilot-light for that purpose, and automatic means adapted to operate with the opening of the gas valve to lock said part in the position first mentioned for preventing ignition of the pilot-light when the gas 105 valve is open.

5. The combination of a combustion chamber, a gas burner therein, a gas valve controlling the flow of gas to the burner, a movable part that when in one position bars 110 access to the burner to light it and when in another position gives access to the burner for that purpose, automatic means adapted to operate with the opening of the gas valve to lock said movable part in the position first mentioned for preventing ignition of the burner, and means for retarding the return of the lock to its unlocking position 115 after the gas has been turned off.

6. The combination with a source of supply 120 of water under pressure, and a source of fuel supply, of a boiler; a burner for heating the boiler; connections between the burner and the source of fuel supply includ- 125 ing a fuel-valve for controlling the admission of fuel to the burner; a valve-actuator connected with and controlling the fuel-valve; connections between the fuel-valve-actuator and the source of supply of water, whereby the valve-actuator may be subjected 130

to the water pressure to open the fuel-valve and admit fuel to the burner; a movable part which when in its closed position bars access to the burner to light it; a lock for 5 said movable part; a lock-actuator adapted to be operated by water pressure; and connections between said lock-actuator and the source of water-supply whereby the lock-actuator and the fuel-valve-actuator may be 10 simultaneously operated by the water-pressure; substantially as shown and described.

7. The combination, with a source of supply of water under pressure, and a source of fuel-supply, of a boiler; a burner for 15 heating the boiler; connections between the burner and the source of fuel-supply including a fuel-valve for controlling the admission of fuel to the burner; a valve-actuator connected with and controlling the 20 fuel-valve; connections between the fuel-valve-actuator and the source of supply of water, whereby the valve-actuator may be subjected to the water-pressure to open the fuel-valve and admit fuel to the burner; a 25 combustion-chamber having a door that gives access to the burner; a lock for the door; a diaphragm operatively connected with the lock; and connections between the diaphragm and the source of water-supply 30 whereby the lock-actuator and the fuel-valve-actuator may be simultaneously operated by the water-pressure; substantially as shown and described.

8. The combination, with a source of supply 35 of water under pressure, and a source of fuel-supply, of a boiler; a burner for heating the boiler; connections between the burner and the source of fuel-supply including a fuel-valve for controlling the 40 admission of fuel to the burner; a valve-actuator connected with and controlling the fuel-valve; connections between the fuel- 45 valve-actuator and the source of supply of

water, whereby the valve-actuator may be subjected to the water-pressure to open the 45 valve and admit fuel to the burner; a combustion-chamber having a door that gives access to the burner; a lock for the door adapted to assume automatically the unlocking position; a lock-actuator operable 50 by water-pressure from the source of supply to hold the lock in engagement with the door; and means for admitting water-pressure simultaneously to the lock-actuator and the fuel-valve-actuator; substantially as 55 shown and described.

9. The combination, with a source of supply of water under pressure, and a source of fuel-supply, of a boiler; a burner for 60 heating the boiler; connections between the burner and the source of fuel-supply including a fuel-valve for controlling the admission of fuel to the burner; a valve-actuator connected with and controlling the fuel-valve; connections between the fuel- 65 valve-actuator and the source of supply of water, whereby the valve-actuator may be subjected to the water-pressure to open the valve and admit fuel to the burner; a combustion-chamber having a door that gives 70 access to the burner; a lock for the door adapted to assume automatically the unlocking position; a lock-actuator operable by water-pressure from the source of supply to hold the lock in engagement with the 75 door; means for admitting water-pressure simultaneously to the lock-actuator and the fuel-valve-actuator; and means for retarding the return of the lock to its unlocking position after the gas has been turned off; 80 substantially as shown and described.
